UNITED STATES PATENT OFFICE.

FRANK H. FISCHER, OF ATLANTIC CITY, NEW JERSEY.

SIGN.

Application filed October 2, 1925. Serial No. 60,098.

To all whom it may concern:

Be it known that I, FRANK H. FISCHER, a citizen of the United States, residing at Atlantic City, in the county of Atlantic and 5 State of New Jersey, have invented new and useful Improvements in Signs, of which the following is a specification.

This invention relates to advertising devices and has particular relation to advertising signs adapted to be placed adjacent a roadway or other conspicuous place.

An object of the present invention is to provide an advertising sign having an artistic appearance so that it will readily attract attention and to further provide a sign which includes a removable display panel constructed and held in place so that it may be easily handled irrespective of the size of the sign and thus permit the display to be 20 changed as often as desired and at a relatively small amount of trouble and expense.

With the above and other objects in view, the invention further includes the following novel features and details of construction, to be hereinafter more fully described, 25 illustrated in the accompanying drawings and pointed out in the appended claims.

In the drawings:—

Figure 1 is a perspective view of the invention with the panel removed.

Figure 2 is a similar view showing the panel partly inserted.

Figure 3 is a like view with the panel in place.

Figure 4 is an enlarged edge view with the panel removed.

Figure 5 is an enlarged fragmentary perspective view of one end of the easel and showing the panel retaining means.

Referring to the drawings in detail where-in like characters of reference denote corresponding parts, the reference character 10 indicates spaced legs adapted to have their lower ends inserted in the ground or otherwise suitably anchored to form a part of an easel. The legs 10 are connected by spaced upper and lower horizontally disposed rails 11 whose opposed edges are rabbeted as shown at 12.

Secured to the rails 11 are the upper and lower members of a frame 13. This frame is preferably of ornamental configuration and may be further ornamented or decorated as desired, the rear face of the upper and lower members of the frame cooperating with the rabbeted portions of the rails 11

to provide guide grooves 14. These grooves are designed to removably receive a panel and the latter is preferably formed of sections 15 as shown in Figures 2 and 3 of the 60 drawings. The sections are designed to be inserted within the opposite ends of the grooves 14 to provide a panel which entirely fills the frames 13.

In order to hold the panel in place and prevent accidental separation of the sections of the panel, one or both of the rails 11, but preferably the lower rail, is provided with an opening 16 near each end. These openings are adapted to removably receive 70 hook-shaped members 17 having a beveled or inclined edge 18. These beveled or inclined edges engage the end walls of the opening 16 so as to provide a wedging action when the members 17 are driven into 75 the openings. These members 17 are designed to abut the opposite ends of the panel and act to removably hold the latter in place and prevent accidental separation of the sections. By tapping the lower ends of 80 the members 17, the latter may be readily removed so as to permit of the removal and replacement of the sections.

The legs 10 are preferably connected by a horizontally disposed strip 19 which acts 85 to reinforce the panel along its horizontal center, the thickness of the strip being equal to the thickness of the opposed edges of the rails 11.

Extending rearwardly and downwardly 90 from the upper ends of the legs 10 are inclined braces 20 whose lower ends are connected as indicated at 21 to the upper ends of anchor stakes 22, the latter being driven into the ground or otherwise suitably secured.

It will be apparent from the foregoing description and accompanying drawing that the invention provides an exceedingly attractive advertising display sign, the artistic character of which will readily attract attention. In addition, its construction permits of frequent changes of panels so that the display matter may be changed as desired. As the panels may be manufactured 95 at a given point and afterward distributed and placed in position, the expense incident to the change of advertising matter will be materially reduced.

The invention is susceptible of various 110 changes in its form, proportions and minor details of construction and the right is here-

in reserved to make such changes as properly fall within the scope of the appended claims.

Having described the invention what is claimed is:—

1. A device of the character described comprising an easel including spaced supporting legs and spaced upper and lower parallel rails, a frame having its top and bottom members secured to said rails and spaced from the legs and a display panel removably positioned between the legs and frame.

2. A device of the character described comprising an easel including spaced supporting legs and spaced upper and lower parallel rails, a frame having its top and bottom members secured to said rails and spaced from the legs and a display panel removably positioned between the legs and frame and said lower rail having an opening therethrough adjacent each end and substantially hook-shaped wedge elements frictionally engaging the walls of the opening and abutting the panel to hold the latter in position.

3. A device of the character described comprising an easel including spaced supporting legs and spaced upper and lower parallel rails, a frame having its top and bottom members secured to said rails and spaced from the legs and a display panel removably positioned between the legs and frame and a sectional display panel removably positioned between the legs and frame

and means at opposite ends of and engaging the panel to prevent separation of the sections.

4. A device of the character described comprising an easel including spaced supporting legs and spaced upper and lower parallel rails having opposed rabbeted edges, a frame having its top and bottom members secured to the rails and cooperating with the walls of the rabbeted edges to provide opposed upper and lower guide grooves, a sectional panel removably positioned within the frame and having its upper and lower edges within the grooves, a horizontally disposed reinforcing strip connecting the legs of the easel and engaging the panel and means engaging opposite edges of the panel to prevent separation of the sections and hold the panel in place.

5. A device of the character described comprising upper and lower parallel rails having opposed rabbeted edges, a frame having its top and bottom members secured to the rails and cooperating with the walls of the rabbeted edges to provide opposed upper and lower guide grooves, a sectional panel removably positioned within the frame and having its upper and lower edges within the grooves, a horizontally disposed reinforcing strip extending behind the frame and engaging the panel and means engaging opposite edges of the panel to hold the panel sections in position.

In testimony whereof I affix my signature.

FRANK H. FISCHER.
